(57) CLAIM

The ornamental design for an absorbent adhesive garment, as shown and described.

DESCRIPTION

FIG. 1 shows a perspective view of an absorbent adhesive garment showing my new design.

FIG. 2 shows a right side elevation view of the absorbent adhesive garment.

FIG. 3 shows a left side elevation view of the absorbent adhesive garment.

FIG. 4 shows a front end elevation view of the absorbent adhesive garment.

FIG. 5 shows a rear end elevation view of the absorbent adhesive garment.

FIG. 6 shows a top plan view of the absorbent adhesive garment; and,

FIG. 7 shows a bottom plan view of the absorbent adhesive garment.

The broken lines shown in the drawings illustrate portions of the absorbent adhesive garment that form no part of the claimed design.

1 Claim, 3 Drawing Sheets
